UNITED STATES PATENT OFFICE.

IGNATZ KREIDL, OF VIENNA, AUSTRIA-HUNGARY.

LOADED SILK AND PROCESS OF LOADING THE SILK.

1,173,195.

Specification of Letters Patent. Patented Feb. 29, 1916.

No Drawing.

Application filed May 26, 1910. Serial No. 563,638.

To all whom it may concern:

Be it known that I, IGNATZ KREIDL, chemist-manufacturer, a subject of the Emperor of Austria-Hungary, and a resident of 5 XXI/1 Kohlgasse 7, Vienna, in the Empire of Austria-Hungary, have invented an Improved Loaded Silk and Process of Loading the Silk; and I do hereby declare the following to be a full, clear, and exact description of the invention, such as will enable others skilled in the art to which it appertains to make and use the same.

This invention relates to the loading or weighting of silk.

15 The processes which have hitherto been utilized for loading silk, consist in increasing the weight of the silk by saturating it with metallic salt solutions. For white silk, chlorid of tin is used almost exclusively. 20 The utilization of these salts has the great objection that the silk is injuriously affected and thereby subjected to loss in strength and elasticity.

The present invention consists in an improved process for loading silk, in which salts of rare earth metals, especially those of zirconium, separately or together, are used in place of the usual salts of tin, for impregnating the material. Other suitable 30 salts of rare earth metals beside those of zirconium, are those of the metals of the groups of the cerite and ytterite earths and of the group of the thorium earths, particularly the salts of the representatives of these 35 groups which are found in group IV of the periodic arrangement. In the case of cerium salts, these should always be used mixed with other salts. The disadvantages of the previous processes are greatly reduced in the improved process according to the present invention. The salts of rare earth metals, especially those of zirconium, possess those qualities which are advantageous for loading silk, namely high atomic 45 weight and the quality of being easily absorbed by the fiber. This latter quality these salts possess owing to their great tendency to assume colloidal formation. Another great advantage resulting from 50 the use of the zirconium salts, or the salts of other rare earth metals, lies in the fact

that they are much cheaper than the salts at present in use, owing to the considerably cheaper raw materials from which they are produced. For example the residual products of the thorium industry may be used, which products have hitherto either not been used or only to a small extent, as well as raw materials, which exist in enormous quantities and only now await utilization 60 such as zirconium earths. As residue of the thorium industry there are obtained known mixtures of salts of the cerite earth metals.

The improved process is carried out similarly to known processes, except in that the salts used are those of rare earth metals. The silk is dipped once or several times in a bath of a salt of rare earth metals, until the desired loading is obtained. As in existing 70 processes the silk is washed between the baths and treated in the usual manner in a bath of alkali-phosphate solution or the like.

Of course all the baths available for the 75 salt of tin loading can be used in place of the alkali phosphate solutions.

What I claim is:—

1. In the process of loading silk, treating the silk with a solution containing a salt of 80 zirconium.

2. As a new article of manufacture, silk loaded with a compound of zirconium.

3. A process of loading silk consisting in dipping silk into a solution of a salt of 85 zirconium, and subjecting said treated silk to a fixing bath.

4. The process of loading silk comprising dipping silk in a solution containing a salt of a metal of the positive series of group IV 90 of the periodic arrangement.

5. As a new article of manufacture silk loaded with a compound of a metal of the positive series of group IV of the periodic arrangement.

6. A process of loading silk, comprising treating silk with a solution containing a salt of a rare earth metal having a high atomic weight and the quality of being easily absorbed by the fiber.

7. A process of loading silk, comprising treating silk with a solution containing

95

100

mixed salts of the rare earth metals having high atomic weights and the quality of being easily absorbed by the fiber.

8. As a new article of manufacture, silk loaded with an absorbed compound of a rare earth metal having a high atomic weight.

9. As a new article of manufacture, silk, loaded with absorbed compounds of rare earth metals having a high atomic weight. 10

In testimony whereof I have signed my name to this specification.

IGNATZ KREIDL.
